RETAINING DEVICE FOR ROTARY HOOKS

Ramon Casas Robert, Geneva, Switzerland, assignor to Mefina S. A. Binningen, a corporation of Switzerland

Application February 28, 1946, Serial No. 650,769
In Switzerland April 18, 1945

7 Claims. (Cl. 112—184)

1

The present invention relates to an improvement in sewing machines having a rotary hook. Such a device generally consists of two essential parts, viz. an inner part called the bobbin holder and adapted to support the bobbin, and an outer part rotating around the bobbin and carrying a hook for catching the loop formed by the upper thread and for passing the latter around the bobbin. The outer part also serves as a support and guide for the bobbin holder and would take the latter with it in its own rotary movement, if it was not for a retaining device which prevents this action and which maintains the bobbin holder stationary.

Numerous designs have been proposed for this retaining device. The simplest means consist in providing the bobbin holder with an extension, bearing against a fixed stop located in the path of the aforementioned extension. As this stop prevents rotation in one direction only, the bobbin holder is free to rotate in the opposite direction for a fraction of a revolution at least. Such a device affords the possibility of removing the goods being sewn from the machine at standstill, without the upper thread remaining hooked in the rotary hook, but it has the inconvenience that, for every stitch, the upper thread having to make its way between said extension and stop, it must overcome an appreciable resistance, varying among other things with the rotational speed of the rotary hook. The upper thread is thus periodically subjected to sudden tensions, causing irregular seams, and noisy operation.

For the purpose of avoiding these inconveniences, numerous retaining devices of various types have been suggested. Most of them have a stop intended to co-operate with bearing surfaces provided on the bobbin holder, said stop being periodically caused to leave the cooperating bearing surface in order to leave a free passage for the upper thread during its travel round the bobbin. Some of these retaining devices comprise two stops, one of them remaining in a fixed position, the other one being carried by a rocking arm, which periodically imparts a backward movement to the bobbin holder for the purpose of liberating the passage in front of the first stop. This solution has the disadvantage of subjecting the bobbin holder to oscillations which cause objectionable vibrations.

In other devices, swinging or rotating members are used having extensions reaching into recesses provided in the bobbin holder for the purpose of keeping same stationary, said extensions leaving periodically the corresponding recess to allow a

2

free passage way for the upper thread. All these constructions have the great inconvenience of not allowing the withdrawal of the work from the machine at standstill, because the loop formed by the upper thread remains caught by the retaining device.

Moreover, in all the constructions mentioned, the stops are provided on the periphery of the rotary hook at points which are either diametrically opposite to each other with respect to the axis of the rotary hook, or located on the same side of a plane passing through the rotary hook and needle axis. This arrangement has the inconvenience of making only a small fraction 15 of the duration of a revolution of the rotary hook available for the period of oscillation or rotation of said retaining device. This means, that the latter must move at a rather high speed and that the resulting stopping forces exerted on 20 the bobbin holder vary in magnitude and direction thus causing very disturbing vibrations.

It has also been proposed to mount the stops on a rotary member, fitted with a slot for the thread. In this arrangement the stops are located 25 in the immediate vicinity of the needle and on the same side of the plane passing through rotary hook and needle axes, thereby producing unfavourably located entrance and exit points of the upper thread.

Moreover, a common drawback of all these 30 constructions is that they provide no means for preventing the bobbin-holder, pulled towards the needle by the lower thread, from bearing against the rotary part of the rotary hook in the most 35 unfavourable portion of its periphery, i. e. against the portion where it is cut away for the passage of the upper thread.

The retaining device, forming the object of this 40 invention, is free from the aforementioned inconveniences. It is distinguished from other retaining devices known, by two bobbin-holder prongs located in close vicinity and on two opposite sides of the needle, and on two different paths around the axis of said rotary hook and by two 45 stops provided each with a single bearing face acting individually on the respective prong so as to continually prevent a rotational displacement of said bobbin-holder in the direction followed by the revolving part of said rotary hook and so as 50 to allow at standstill of said machine said bobbin-holder to perform a substantial rotational displacement in the opposite direction under the action of a slight pull exerted on said upper thread, thus allowing the work to be removed from said machine at standstill.

Simply stated, further objects of the invention are:

- (a) The positioning of said stops one in front and one in back of the axis of said needle in order to afford the greatest possible time interval between the instants of opening of the passage ways for the entrance and for the exit of said upper thread;
- (b) The shaping of said prongs in such a way that the force exerted on them by said stops partially counteract the pull exerted during sewing by said lower thread;
- (c) The shaping of said prongs for a bobbin-holder to be used in a vertical axis rotary hook in such a way that the force exerted on them contains an upwardly directed vertical component releasing partially the vertical force exerted by the weight of said bobbin and bobbin-holder in said rotary hook;
- (d) Further minor improvements which will become apparent to one skilled in the art in the course of the following description.

The drawings show by way of example a form of embodiment of the invention.

Figs. 1, 2 and 3 are perspective views of the device seen in three different working positions.

Fig. 4 is a plan view of a portion of the device.

Fig. 5 is a perspective view of the device shown with its connections to a work feeding mechanism of a sewing machine.

The device represented in the drawings is intended for use with a vertical axis rotary hook, making two revolutions for every stitch. The rotary hook comprises a rotary and a stationary part. The rotary part comprises a cup 11, whose cylindrical part is cut away at 12 so as to form a hook 13, substantially tangential to the needle 14 of a sewing machine not shown. Said cup 11 is mounted rigidly on a shaft 15 driven in rotation by a shaft 16 in the direction of the arrow by means of two bevel gears 17 and 18.

The rotational speed of shaft 15 is double that of driving shaft 16. Said cup 11 serves as a support and housing for the stationary part of the rotary hook, i. e. a bobbin-holder 19 containing a bobbin 20 carrying the lower thread 21 of the sewing machine. The purpose of hook 13 is to catch a loop formed by the upper thread 22 and to pass it around said bobbin. Bobbin-holder 19 held and guided by said cup 11 would be carried along by friction by the mere rotation of said cup if it was not prevented from so doing by a retaining device, forming the object of this invention and which maintains said bobbin-holder stationary.

The bobbin-holder is provided with a horizontal extension 23 cut away so as to form two prongs 24 and 25 butting against two bearing faces 26 and 27 provided on an oscillating member, whose shaft 28, parallel with said driving shaft 16, is made to oscillate in fixed bearings (not shown). Shaft 16 imparts an oscillating movement to shaft 28 by means of a cylindrical cam 29 mounted eccentrically on said shaft and a lever 30 fastened to said oscillating shaft. One end of said lever is bent so as to form a collar around shaft 28 and clamped by a screw 31, permitting an angular adjustment of said lever on said shaft 28. The other end of said lever is maintained in continuous contact with cam 29 by a spring 32, wound on shaft 28, one end of said spring resting on a fixed point, the other end being held on lever 30 by a prong 33. Shaft 28 has, riveted to it, an arm 34 with an offset vane 35 and a groove, guiding a regulatable

small plate 36. A clamping screw 37 allows the aforementioned plate to be adjusted relative to the shaft 28. The surfaces 26 and 27 acting as stops for the prongs 24 and 25 are provided respectively on the edges of vane 35 and sliding plate 36.

For reasons, which shall become apparent later, it must be noted that the surfaces of contact between stops and prongs are chosen on two different radii with respect to the rotary hook axis so as to be located on different paths around said axis. Said surfaces or butting faces 26 and 27 are portions of conical surfaces having their axis coinciding with that of shaft 28 as shown in Fig. 4. The result of this arrangement is that the point of contact of each of said butting faces with its corresponding bobbin-holder prong 24 and 25 has its instantaneous motion directed in the plane tangent to said butting face at said point of contact. Thus, the oscillation of said stops 35 and 36 causes no motion of the bobbin-holder around the rotary hook axis.

It should be noted that said contact points between said stops and said prongs are located at two points practically opposite to one another with respect to the needle axis 14 (see Fig. 4, one in back and one in front of said axis). Stops 26 and 27 thus prevent bobbin-holder 19 from being frictionally carried around by cup 11.

The oscillatory motion of axle 28, synchronised with the motions of hook 13 and needle 14 has for its object to alternately cause one or the other stop to retreat from the respective prong 24 or 25, thereby preparing a free passage way for that strand of the loop formed by the upper thread which is carried around by the hook.

Describing the various functions from the point of view of the operator of said sewing machine with the rotary hook on the left of the needle axis:

Fig. 1 shows the device at the moment arm 34 reaches the upper dead point of its movement. Rear stop 27 is in contact with rear prong 25 and maintains bobbin-holder 19 stationary. Loop 22 just formed by the needle in its upward movement between prongs 24 and 25 has been caught by hook 13 which is about to pass same around bobbin-holder 19. As the inner strand of said loop is retained by the back edge of front prong 24 the outer strand crosses the free passage way momentarily provided between the front edge of said front prong and the back edge 26 of front stop 35.

In the position shown in Fig. 2, the hook keeps drawing the loop around the bobbin-holder while arm 34 progressively moves downwards. Front stop 35 makes contact with front prong 24 and rear prong 25 still bears against butting face 27. At this point, it is necessary to note that, the aforesaid clamping screw 37 allows the device to be adjusted during assembly so as to enable both prongs to give simultaneous contact with their respective stop.

Fig. 3 shows the device shortly before arm 34 has reached its lower dead point. Prong 24 remains in contact with butting face 26, while a passage way has been freed between front edge of rear prong 25 and butting face 27 of rear stop 36. Strand 22 of the loop being pulled by the thread tensioning device (not shown) of the sewing machine, the loop embracing rear prong 25 decreases in size and sliding along the edges of prong 25 escapes from the rotary hook before it may be caught again by hook 13.

Subsequently, arm 34 has its motion reversed,

it moves upwards and reaches again the position shown in Fig. 1; during this time, the hook idles and performs a complete revolution.

From the above it may be seen that the described device has the following advantages:

- (1) The arrangement of stops and prongs prevents the rotation of the bobbin-holder in one direction only, the direction in which said bobbin-holder would be carried by the rotary part of the rotary hook. Owing to this feature and to the shapes given to said stops and prongs, when the machine stands still in a position not very far from that corresponding to the entrance or to the exit of the upper thread, the work may be removed freely from the sewing machine. The upper thread under a very slight pull may be freed from the rotary hook by causing the bobbin-holder to rotate backwards a portion of a revolution.
- (2) Both stops are placed in the immediate vicinity and on two opposite sides of the needle axis, the entrance of the loop being located in front of the needle axis and the exit of the loop being located in back of the needle axis. This arrangement affords the largest possible time-interval between the instants of opening of the passage ways for the entrance and for the exit of the upper thread, thus allowing for a comparatively large amplitude for a reasonably small velocity of the oscillating stops to be chosen.
- (3) By reason of the vicinity of the two stops and of their position with respect to the rotary hook axis, the forces exerted by them on the prongs of the bobbin-holder have substantially the same magnitude and direction for all positions of said stops. There is thus no alternating force capable of causing vibrations of the bobbin-holder.
- (4) The resting edge of the two prongs as seen from the top (Fig. 4) leans backwards (angle d) in such a way that the forces exerted by the stops on the bobbin-holder counteract to a certain extent the tension exerted by the lower thread on the bobbin towards the needle. This feature prevents the bobbin-holder from bearing on the cylindrical portion of the cup in the vicinity of the needle axis, thus avoiding an unfavourable guiding of the bobbin-holder in the cup, which would exist at the moment where both cut-outs in bobbin-holder and cup come in coincidence during the rotation of the cup, this relative position being shown in Fig. 3. Owing to this particular arrangement the guiding of the bobbin-holder on its periphery takes place at a point substantially remote from the cut-out of the bobbin holder 19 say practically in the direction of arrow 38.
- (5) The forces exerted by the stops on the bobbin-holder have a vertical component acting upwards, with the effect of reducing the frictional forces on the horizontal bearing surfaces of the bobbin-holder in the cup. This upwards component results from the fact, that the butting faces of the stops are not vertical at their point of contact with the bobbin-holder prongs. In fact, the axis of revolution of the conical surfaces 29 and 27 of stops which coincide with that of the axle 28 is located at a level much lower than that of the prongs 24 and 25 of the bobbin holder 19.

Fig. 5 shows by way of example, how the described device can be combined with an automatic work-feeding mechanism of compact design. The oscillating member of the bobbin-holder retaining device and the automatic feeding mechanism are operated in common by eccentric 29 fastened to driving shaft 16. The feeding of the work is produced by a toothed plate 41, fastened to a moving arm 48, whose lower part is pivoted on a shaft 43 carried by a fork shaped member 44 oscillating with its shaft 45 in stationary bearings not shown. Both prongs 46 of said fork embrace cam 29. On its upper part, arm 42 is driven by a connecting rod 47 connecting a shaft 48 fastened to said arm with a shaft 49 driven by a connecting rod 52 driven itself by aforesaid eccentric 29. Fork shaped member 44 imparts a substantially vertical motion to toothed plate 41 while connecting rod 52 cooperating with a crank 50, pivoted in 51 and equipped with shaft 49 imparts a substantially horizontal motion to said toothed plate 41. The amplitude of latter said motion may be altered at will through a displacement of pivot 51 bearing in a cranked shaft 53, whose angular position may be maintained in various positions by means of a control handle 54 running over a graduated scale 55 and resting on the knurled edge of said scale. A change in the position of said control handle modifies the rate and the direction of the automatic feed of the work owing to the fact that pivot 51 may be located at a point substantially higher or lower than the average position of shaft 49.

It is apparent that without departing from the spirit and scope of the invention, it is possible to replace the angular oscillatory movement of aforesaid stops 35 and 36 by a rectilinear oscillatory movement or more generally by a to-and-fro movement.

I claim:

1. In a sewing machine having a reciprocating needle for carrying an upper thread and a bobbin for containing a lower thread, a rotary hook having an axis of rotation parallel to the path of reciprocation of the needle, said rotary hook including a rotary member having a hook and a recess, a bobbin carrier mounted in said recess, a shaft for rotating said rotary member about its axis, a pair of spaced arms extending substantially radially outwardly from the bobbin carrier beyond the rotary hook, a pair of movable stops cooperating with said arms to prevent rotation of the bobbin carrier in the direction of rotation of the rotary hook, and means for oscillating said stops in a direction generally parallel to the shaft for driving the rotary member to alternately position one stop in engagement with its cooperating arm and move the other stop away from contact with its cooperating arm to enable a thread loop to pass between the same.
2. In a sewing machine having a reciprocating needle for carrying an upper thread and a bobbin for containing a lower thread, a rotary hook having an axis of rotation parallel to the path of reciprocation of the needle, said rotary hook including a rotary member having a hook and a recess, a bobbin carrier mounted in said recess, a shaft for rotating said rotary member about its axis, a pair of spaced arms extending substantially radially outwardly from the bobbin carrier beyond the rotary hook, a pair of movable stops cooperating with said arms to prevent rotation of the bobbin carrier in the direction of rotation of the rotary hook, and means for oscillating

said stops in a direction generally parallel to the shaft for driving the rotary member to alternately position one stop in engagement with its cooperating arm and move the other stop away from contact with its cooperating arm to enable a thread loop to pass between the same, said oscillating means being driven at a speed relative to the rotary member driving shaft such that the rotary member makes two revolutions for each to and fro movement of the stops.

3. In a sewing machine having a reciprocating needle for carrying an upper thread and a bobbin for containing a lower thread, a rotary hook having an axis of rotation parallel to the path of reciprocation of the needle, said rotary hook including a rotary member having a hook and a recess, a bobbin carrier mounted in said recess, a shaft for rotating said rotary member about its axis, a pair of spaced arms extending substantially radially outwardly from the bobbin carrier beyond the rotary hook, a pair of movable stops cooperating with said arms to prevent rotation of the bobbin carrier in the direction of rotation of the rotary hook, and means for oscillating said stops in a direction generally parallel to the shaft for driving the rotary member to alternately position one stop in engagement with its cooperating arm and move the other stop away from contact with its cooperating arm to enable a thread loop to pass between the same, said means comprising an oscillating shaft positioned perpendicularly to the shaft driving the rotary member and carrying said stops, a crank arm fixed to the oscillating shaft, a cam shaft, a cam on the cam shaft cooperating with the crank arm for driving the oscillating shaft, transmission means connecting the cam shaft to the shaft driving the rotary member so that the cam shaft rotates at $\frac{1}{2}$ the speed of rotation of the other shaft, and the stops make a single to and fro movement for each two revolutions of the rotary hook carrying member.

4. In a sewing machine having a reciprocating needle for carrying an upper thread and a bobbin for containing a lower thread, a rotary hook having an axis of rotation parallel to the path of reciprocation of the needle, said rotary hook including a rotary member having a hook and a recess, a bobbin carrier mounted in said recess, a shaft for rotating said rotary member about its axis, a pair of spaced arms extending substantially radially outwardly from the bobbin carrier beyond the rotary hook, a pair of movable stops cooperating with said arms to prevent rotation of the bobbin carrier in the direction of rotation of the rotary hook, and means for oscillating said stops in a direction generally parallel to the shaft for driving the rotary member to alternately position one stop in engagement with its cooperating arm and move the other stop away from contact with its cooperating arm to enable a thread loop to pass between the same, said stops each having a single engaging surface coacting individually with the arms, said stops being located at different distances from the shaft of the rotary member and said arms being of different lengths to cooperate and prevent angular displacement of said bobbin carrier in the direction of rotation of the rotary member only, and permitting upon stopping the machine an opposite angular displacement of the bobbin carrier to enable removal of work from the machine.

5. In a sewing machine having a reciprocating needle for carrying an upper thread and a bobbin for containing a lower thread, a rotary hook hav-

ing an axis of rotation parallel to the path of reciprocation of the needle, said rotary hook including a rotary member having a hook and a recess, a bobbin carrier mounted in said recess, a shaft for rotating said rotary member about its axis, a pair of spaced arms extending substantially radially outwardly from the bobbin carrier beyond the rotary hook, a pair of movable stops cooperating with said arms to prevent rotation of the bobbin carrier in the direction of rotation of the rotary hook, and means for oscillating said stops in a direction generally parallel to the shaft for driving the rotary member to alternately position one stop in engagement with its cooperating arm and move the other stop away from contact with its cooperating arm to enable a thread loop to pass between the same, said stops each having a contact surface movable along the arc of a circle tangent to the cooperating surface of the arm to avoid vibration of the bobbin carrier.

6. In a sewing machine having a reciprocating needle for carrying an upper thread and a bobbin for containing a lower thread, a rotary hook having an axis of rotation parallel to the path of reciprocation of the needle, said rotary hook including a rotary member having a hook and a recess, a bobbin carrier mounted in said recess, a shaft for rotating said rotary member about its axis, a pair of spaced arms extending substantially radially outwardly from the bobbin carrier beyond the rotary hook, a pair of movable stops cooperating with said arms to prevent rotation of the bobbin carrier in the direction of rotation of the rotary hook, and means for oscillating said stops in a direction generally parallel to the shaft for driving the rotary member to alternately position one stop in engagement with its cooperating arm and move the other stop away from contact with its cooperating arm to enable a thread loop to pass between the same, the contact surfaces of the stops being approximately parallel to each other and to the corresponding surfaces of the arms, and said surfaces being oriented in such a manner that the bobbin carrier is subjected during operation of the machine to a force of approximately constant value and the latter direction being approximately opposite to the force exerted on the carrier by the bobbin thread when tension is applied to said thread.

7. In a sewing machine having a reciprocating needle for carrying an upper thread and a bobbin for containing a lower thread, a rotary hook having an axis of rotation parallel to the path of reciprocation of the needle, said rotary hook including a rotary member having a hook and a recess, a bobbin carrier mounted in said recess, a shaft for rotating said rotary member about its axis, a pair of spaced arms extending substantially radially outwardly from the bobbin carrier beyond the rotary hook, a pair of movable stops cooperating with said arms to prevent rotation of the bobbin carrier in the direction of rotation of the rotary hook, and means for oscillating said stops in a direction generally parallel to the shaft for driving the rotary member to alternately position one stop in engagement with its cooperating arm and move the other stop away from contact with its cooperating arm to enable a thread loop to pass between the same, said means comprising an oscillating shaft positioned perpendicularly to the shaft driving the rotary member and carrying said stops, a crank arm fixed to the oscillating shaft, a cam shaft, a cam on the cam shaft cooperating with the crank arm for driv-

ing the oscillating shaft, transmission means connecting the cam shaft to the shaft driving the rotary member so that the cam shaft rotates at $\frac{1}{2}$ the speed of rotation of the other shaft, and the stops make a single to and fro movement for each two revolutions of the rotary hook carrying member and a work feed mechanism having a cam follower cooperating with said cam for operating the same.
